UNITED STATES PATENT OFFICE

2,010,132

DEVICE FOR COOLING THE BODY BY MEANS
OF LIGHT VOLATILE CHEMICALS

Johannes Christian Bischoff, Kiel, Germany

Application November 7, 1933, Serial No. 697,087
In Germany May 31, 1933

6 Claims. (Cl. 62—168)

A rapid cooling of the body is attained by dipping the hands and arms into a basin containing cold water or by holding the forearm under a cool but not too strong jet of water from the water main, so that the jet runs just onto the artery. This method can, however, be employed only when cooled water, ice or the like is available. Cooling devices are also known in which the temperature of the body can be treated by application of absorbent substances. In these cooling devices, however, the cooling substance must be renewed.

Contrary hereto the cooling according to the invention is attained in that the cooling medium leaves the container and enters into an evaporating device in which it is caused to evaporate by the admittance of air, so that the cooling effect is obtained. The cooling substance need not be removed for renewal but the container is merely refilled as soon as the volatile substance has been consumed which is fed from the container as desired.

This is attained according to the invention in that the cooling medium is in a container which is connected directly or by means of a tube with an evaporating device, and that the admission of the cooling substance into the evaporating device can be regulated directly or by means of a valve or screw. The evaporating device is closed on the side adjacent the body so that no direct moistening of the skin takes place, and the lateral edges are rolled inwards in order to prevent overflowing. This device may also be employed without absorbent material.

An embodiment of the invention is illustrated by way of example in the accompanying drawing, in which:—

Fig. 1 is a top plan view of the container and the evaporating device.

Fig. 2 is a front elevation.

Fig. 3 is a side elevation.

Fig. 4 shows by way of example a container for head cooling.

Fig. 5 shows an evaporator without container.

The device for cooling the blood temperature consists of a container *a* for the cooling medium. The container is provided with a filling screw *b*. In order to avoid the necessity of complete removal of the screw *b* for filling its shank is hollow and provided with an aperture *c* through which the container *a* can be filled. The evaporating device extending from the container *a* consists, in the example illustrated, of a thin metal plate *d* the edge *e* of which is rolled inwards to form a channel.

The volatile substance is supplied to the evaporating plate *d* through a tube *g* fixed on the container *a* and provided at its end with a distributor head *h* by means of which the volatile substance is distributed over the absorbent cellulose material *z* placed in the evaporating plate *d*, so that it can evaporate. The volatile substance may be supplied directly or by a wick *i* to the distributor head *h*, and the quantity can if necessary be regulated by a valve or screw *k* arranged in the feed tube *g*. Eyes *l* are provided on the device *a* to enable it to be fixed over the artery at the wrist by means of straps, elastic bands or clips.

Fig. 4 shows as example of application a device for cooling the head in a tropical helmet, the container *a* being arranged in the space above the sweat band whereas several evaporating plates *d*, connected with the container *a* by tubes, are arranged on the sweat band so that the temples and forehead are cooled thereby.

The construction of the device depends in other respects upon the volatile substance and consequently as to whether the device is intended for cooling the temperature of the body or the wrists, the heart, the temples or the like, or for cooling an inflammation on the body, for example on the legs. Volatile etheric oils or the like or also crystallized chemicals such as dry ice, and the like which generate cold on volatilizing, may be employed as source of cold. If volatile etheric oils, which do not irritate the skin, are employed the evaporating plate and the edge thereof may be provided with holes adapted to be entirely or partly closed by a slide or by some other known means. If stronger chemicals are employed or if the device is to be used by persons having a very sensitive skin, no holes are provided in the evaporating plate and in the edge thereof so that no volatile liquid can come into contact with the skin.

By dry ice is understood solid carbon dioxide which is accommodated in the container and is slowly liquefied and volatilized by the admission of air. These substances may contain refreshing perfumes.

The evaporating device may also be arranged directly below the container *a* registering with the same and separated therefrom by an air gap. Finally, other combinations are possible, for example the arrangement of the container *a* in a circle around the evaporating device.

The device may be constructed as a piece of

jewelry and ornamented with stones, a watch or the like.

The advantage of the device for cooling the arteries consists in that its employment is not restricted to any particular place and that its wearer can continue to carry out his ordinary duties.

I claim:—

1. A device for cooling the body with the aid of a volatile refrigerant, comprising in combination a refrigerant container, and an evaporator connected with said container, said evaporator including a plate adapted to bear against the skin, a tube extending from said container, and a distributor head on the end of said tube, and means adapted to distribute the refrigerant over said plate.
2. A device for cooling the body with the aid of a volatile refrigerant, comprising in combination a refrigerant container and an evaporator connected with said container, said evaporator including a plate adapted to bear against the skin, a tube extending from one end of said container over said plate, a distributor head on the end of said tube and adapted to distribute the refrigerant over said plate, and means in said tube for regulating the flow of refrigerant from said container to said head.
3. A device for cooling the body with the aid of a volatile refrigerant, comprising in combination a refrigerant container and an evaporator connected with said container, said evaporator including a plate adapted to bear against the skin, a tube extending from one end of said container over said plate, a distributor head on the end of said tube and adapted to distribute the refrigerant over said plate, and a screw in said

tube for regulating the flow of refrigerant from said container to said head.

4. A device for cooling the body with the aid of a volatile refrigerant, comprising in combination a refrigerant container and an evaporator connected with said container, said evaporator including a plate adapted to bear against the skin, a tube extending from one end of said container over said plate, a distributor head on the end of said tube and adapted to distribute the refrigerant over said plate, means in said tube for regulating the flow of refrigerant from said container to said head, and a filling screw on the end of said container remote from said tube having a hollow shank and an aperture to allow the filling of said container without completely removing said screw.

5. A device for cooling the body with the aid of a volatile refrigerant, comprising in combination a refrigerant container, an evaporator connected to said container, and including a plate closed on the side adjacent the skin, means for admitting refrigerant from said container to said evaporator, and edges on said plate rolled in to form a channel adapted to prevent the volatile substance from coming into contact with the skin.

6. A device for cooling the body with the aid of a volatile refrigerant, comprising in combination a refrigerant container, an evaporator extending from one end of said container and including a plate adapted to bear against the skin, means for admitting refrigerant from said container to said evaporator, and eyes one on each side of said container adapted to secure the device on the part of the body to be cooled.

JOHANNES CHRISTIAN BISCHOFF.
